UNITED STATES PATENT OFFICE.

JOHN JUHÁSZ, OF NEW YORK, N. Y.

CARBURETER.

1,144,206.

Specification of Letters Patent. Patented June 22, 1915.

Application filed October 11, 1913. Serial No. 794,638.

To all whom it may concern:

Be it known that I, JOHN JUHÁSZ, a subject of the King of Hungary, and resident of the city of New York, in the county of New York and State of New York, have invented certain new and useful Improvements in Carbureters, of which the following is a specification.

The present invention relates to a carbureter for use in connection with internal combustion engines, although applicable in various other ways.

The invention relates more particularly to that type of carbureters in which air is caused to flow at high velocity past the discharge end of a permanently open liquid hydrocarbon supply conduit, whereby the liquid hydrocarbon is entrained and atomized and sprayed, the resultant combustible mixture being composed of air and liquid hydrocarbon gasified or vaporized in part and in part sustained in liquid form.

One of the objects of the present invention is to provide a carbureter which is adapted to furnish a predetermined mixture to an engine for the several speeds at which the latter may be running without readjustment of the carbureter parts.

Another object of the invention is to produce a carbureter which requires no further attention than the manipulation of the throttle.

A further object of the invention is to construct a carbureter which will thoroughly mix and commingle the air with the liquid hydrocarbon previous to the passage into the combustion chamber.

Still a further object of the invention is to provide a device of this character, which is efficient in operation, simple in construction and which can be manufactured on a commercial scale, or in other words which is not so difficult to produce as to be beyond the reasonable cost of such an article.

With these and other objects in view, which will more fully appear as the nature of the invention is better understood, the same consists in the combination, arrangement and construction of parts hereinafter fully described, pointed out in the appended claims and illustrated in the accompanying drawings, it being understood that many changes may be made in the size and proportion of the several parts and details of construction within the scope of the appended claims without departing from the spirit or

sacrificing any of the advantages of the invention.

One of the many possible embodiments of the invention is illustrated in the accompanying drawings, in which:

Figure 1 is a vertical central section taken through a carbureter constructed in accordance with the present invention; Fig. 2 is a front elevation, partly in section, of the same; Fig. 3 is a plan view of the throttle used in connection with the carbureter; Fig. 4 is a section taken on line 4—4 of Fig. 3; Fig. 5 is a section taken on line 5—5 of Fig. 3; Fig. 6 is a section taken on line 6—6 of Fig. 3; Fig. 7 is an enlarged view of one of the fuel supply nozzles; Fig. 8 is a side elevation of the throttle operating means; and Fig. 9 is a section taken through the throttle and its casing, the throttle being in its closed position.

In the drawings, the numeral 10 indicates a casing having formed therein a plurality, in the present case three, L-shaped passages 11, constituting individual carbureter chambers. The lower ends 12 of these passages terminate in the side of the casing and form the main air inlets to the carbureter chambers, while their upper ends 13 terminate in the upper face of the casing and constitute the outlets through which the charges formed in the chambers pass to the cylinders of the engine. The carbureter chambers are independent of each other, each of the same being a separate and distinct charge forming device, their number being adapted to be varied according to the requirements. Between the outlets of the casing 10 and the pipe leading to the manifold of the internal combustion engine is inserted a joining member 10', the lower end 10'' of which is flattened, as clearly shown in Fig. 1 of the drawings, and extended, as shown in Fig. 2 of the drawings, for a purpose hereinafter to be described.

Projecting upward through the body of the casing and in each of the passages 11 is disposed a fuel supply nozzle 14. These nozzles communicate with a transverse passage 15 in the casing 10, said passage being supplied with liquid hydrocarbon through a channel 16 from a lateral float chamber 17, in which a float 18, acting upon levers 19, 19, which are suitably attached to a needle valve 20, keeps the level of the liquid hydrocarbon always the same. The needle valve 20 controls the inlet 21 to the float chamber,

said inlet being connected by a pipe 22 with a supply tank. Obviously float chambers of other types could just as well be made use of, the one herein described being disclosed 5 for purposes of illustration only.

The construction of all of the fuel discharge nozzles 14 is alike. Each nozzle comprises a tubular member 23, the lower enlarged end 24 of which is exteriorly screw threaded, said screw threads meshing with those of bores 25 in the casing, squared heads 26 upon the nozzles serving to facilitate their mounting upon the casing. The nozzles are inserted through interiorly screw 10 threaded bores 27, which, after the nozzles have been put in place, are closed by plugs 28. The upper end of each nozzle is closed by a screw 29, having a tapering point 30. Near its upper end each nozzle is provided 15 with a plurality of radially extending discharge openings 31, from which extend longitudinal slots 32 to its upper end. The liquid hydrocarbon, which is kept in the nozzles at a level slightly below that of the 20 openings 31, is drawn out by air currents produced by the suction of the pistons and passing the said nozzles. Inasmuch as the upper ends of the nozzles are closed, the liquid hydrocarbon flows through the discharge openings 31 and the slots 32 in substantially horizontal directions, the points 25 of the screws 29 acting as deflectors. Owing to this arrangement, a flow of the liquid hydrocarbon will be induced substantially 30 at right angles to the direction of the flow of the air, thereby resulting in a thorough mixture of the air and liquid hydrocarbon 35 in the carbureting chambers.

Above the fuel discharge nozzles 14 is 40 formed in the casing 10 a horizontal hollow cylindrical enlargement 33, the ends of which are closed by heads 34, upon which are formed bearings 35 for the journals 36 of a cylindrical throttle valve 37, that is 45 located within said enlargement. The body of the throttle is provided with three openings, corresponding to the three passages 11, the said openings being denoted by the numerals 38, 39 and 40. These openings extend diametrically through the body of the 50 throttle, and are substantially cylindrical. The cross section of the opening 40 corresponds exactly to the cross section of its respective passage 11. The cross section of the 55 central portion of the opening 39 corresponds also to the cross section of its passage 11, increasing, however, from said central portion to its upper end 41, and in a similar manner to its lower end 42, the leading edge 41' of the upper end being in advance of its normal section. In a similar 60 manner corresponds the cross section of the central portion of the opening 38 to that of its corresponding passage 11, this section 65 increasing toward its upper end 43, and in

a similar manner toward its lower end 44, the leading edge 45 at its upper end being in advance of its normal cross section, and to a greater degree than that of the opening 39. The throttle is adapted to be actuated 70 by means of a lever 46, which is fixedly attached to one of its journals, a fixed stop 47 being formed upon one of its heads 34, such stop limiting the closing of the throttle, and an adjustable stop, in the form of a set 75 screw 48, being provided also upon said head for limiting and adjusting the opening of the throttle.

Around the nozzles is formed a jacket 49, through which a heating medium may circulate through pipes 50, 50, which are connected, for instance, with the water cooling system of the engine, for the purpose of maintaining an even temperature around the fuel supply nozzles.

In the valve chamber, that is in the cylindrical enlargement 33 of the carbureter, are formed three apertures, denoted by the numerals 51, 52 and 53. Each of these apertures leads to one of the L-shaped passages 90 11, constituting the three carbureter chambers. The aperture 51 is disposed in such a manner that, when the throttle is in its closed position (Fig. 9), the edge 54 of the opening 38 in the body of the throttle permits air to flow into the said opening. This aperture 51 is, however, closed as soon as the throttle is moved toward its opening position, and kept closed until the throttle is fully opened, in which case the edge 55 95 of the opening 38 uncovers again the said aperture, as shown in Fig. 1 of the drawings. The openings 52 and 53 are disposed in such a manner upon the cylindrical enlargement 33 of the casing that the throttle covers the 100 same until swung to its fully open position, when the edge 56 of the opening 39 and the edge 57 of the opening 40 uncover the apertures 52 and 53, respectively. The purpose of this arrangement will be hereinafter explained.

The operation of the carbureter is as follows: The sizes of the openings 31 and slots 32 in the nozzles are determined by experiments, it being noted that those in the nozzle in that passage 11 which is controlled by the opening 38 are the largest, those co-operating with the opening 39 smaller, and those in the nozzle co-operating with the opening 40 still smaller. It is to be observed that when the throttle is in its closed position, that is to say when the lever 46 abuts against the stop 47, the openings 39 and 40 are out of alignment with their corresponding passages 11, the apertures 52 and 53 being closed. The opening 38 is, however, not in its fully closed position, that is to say a minimum opening is always provided sufficient to permit of a flow of air past the supply nozzle in the middle passage 110 125 130

11 to furnish the proper amount of combustible mixture for the motor when running slow without any load applied thereto, for instance if the engine is mounted upon an 5 automobile and the latter is at its full stop. The aperture 51 is open (Fig. 9) to permit air to flow into the opening 38 so as to make the mixture flowing therethrough sufficiently lean for a slow running engine to which no 10 load is applied. In shifting the throttle to open it, first the opening 38 becomes effective, the aperture 51 being closed immediately, then the opening 39 becomes effective, and finally the opening 40, or in other words 15 the passages 11 are gradually and in succession opened. Inasmuch as these passages are not interconnected, the same effect will be obtained as if a plurality of independent carbureters were provided. These carbureters, however, are caused to coöperate inasmuch as they are controlled by a common 20 throttle in such a manner that the second in the series starts its operation before the first in the series becomes fully operative, 25 and the third in the series furnishes a combustible mixture before the second in the series is rendered fully operative. When the throttle is in its fully open position, the apertures 51, 52 and 53 are uncovered, permitting 30 auxiliary air to enter the individual carbureter chambers, said auxiliary air making the mixture flowing through said chambers more uniform and homogeneous.

The joining member 10' forms a mixing 35 chamber for the combustible mixtures passing through the carbureter chambers. As long as only the middle carbureter chamber is operative, the mixture flows to the central passage 11 in a straight line through the 40 joining member into the pipe leading to the manifold. When, however, one or both of the remaining carbureter chambers become effective, the individual mixtures flowing through the side chambers 11 into the said 45 mixing chamber are deflected by the inclined walls 58 thereof and caused to intermingle with the mixture flowing through the central chamber.

If the sizes of the discharge openings of 50 the three fuel supply nozzles are once determined, and the set screw 48 is placed in the proper position, no further adjustment of the parts will be necessary. By the use 55 of a number of nozzles with the properly proportioned discharge openings, the proper amount of liquid hydrocarbon for the air passing the nozzles is furnished. When the charge flows through the opening 38 only, which is at slow speed, the most efficient 60 mixture for that speed is obtained. When the opening 39 becomes operative, a different mixture, a combination of those flowing through the openings 38 and 39 will be obtained, which is best fitted for the motor 65 when the latter is running at a second pre-

determined speed. When the charge flows through all of the three openings, a combination of the three individual mixtures will be obtained. The throttle valve thus not only controls the quantity of the charge, but 70 also its quality.

What I claim is:—

1. In a carbureter, the combination with a plurality of carbureter chambers, each chamber having a main air inlet and an outlet, of a fuel supply nozzle in each chamber, a valve casing interposed between said inlets and outlets having a plurality of apertures through which air is adapted to flow into said chambers, and a cylindrical throttle in 75 said casing common to all of said chambers having openings through which communications are adapted to be established between the main air inlets of said chambers and their respective outlets, said openings being 80 of varying sizes and said throttle being rotatable, whereby said communications are established gradually and in succession, said throttle controlling the passage of air through said apertures into said carbureter 85 chambers.

2. In a carbureter, the combination with a plurality of carbureter chambers, each chamber having a main air inlet and an outlet, of a fuel supply nozzle in each chamber, a valve casing interposed between said inlets and outlets having a plurality of apertures 95 through which air is adapted to flow into said chambers, and a cylindrical throttle in said casing common to all of said chambers 100 having openings through which communications are adapted to be established between the main air inlets of said chambers and their respective outlets, said openings being of varying sizes and said throttle being rotatable, whereby said communications are established gradually and in succession, said throttle controlling said apertures and 105 permitting air to flow therethrough into said carbureter chambers when shifted to its 110 fully open position.

3. In a carbureter, the combination with a plurality of carbureter chambers, each chamber having a main air inlet and an outlet, of a fuel supply nozzle in each chamber, one of said nozzles being permanently 115 in communication with the outlet of its chamber, a valve casing interposed between said inlets and outlets having a plurality of apertures through which air is adapted to 120 flow into said chambers, and a cylindrical throttle in said casing common to all of said chambers having openings through which communications are adapted to be established between the main air inlets of said 125 chambers and their respective outlets, said openings being of varying sizes and said throttle being rotatable, whereby said communications are established gradually and in succession, said throttle controlling said 130

apertures and permitting air to flow while the throttle is in its closed position into that chamber the nozzle of which is permanently in communication with the outlet of its chamber, stopping such flow as soon as the throttle is shifted toward its open position, and allowing the passage of air into all of said chambers through said apertures when said throttle is fully opened.

10 4. In a carbureter, the combination with a plurality of carbureter chambers, each chamber having a main air inlet and an outlet, of a fuel supply nozzle in each chamber, a valve casing interposed between said inlets and outlets having a plurality of apertures through which air is adapted to flow into said chambers, a cylindrical throttle in said casing common to all of said chambers having openings through which communications are adapted to be established between the main air inlets of said chambers and their respective outlets, said openings being of varying sizes and said throttle being rotatable, whereby said communications are established gradually and in succession, said throttle controlling the passage of air through said apertures into said carbureter chambers, and a mixing chamber into which the combustible mixtures are conducted through said outlets.

5. In a carbureter, the combination with a plurality of carbureter chambers, each chamber having a main air inlet and an outlet, of a fuel supply nozzle in each chamber, a valve casing interposed between said inlets and outlets having a plurality of apertures through which air is adapted to flow into said chambers, a cylindrical throttle in said casing common to all of said chambers having openings through which communications are adapted to be established between the main air inlets of said chambers and their respective outlets, said openings being of varying sizes and said throttle being rotatable, whereby said communications are

established gradually and in succession, said throttle controlling said apertures and permitting air to flow therethrough into said carbureter chambers when shifted to its fully open position, and a mixing chamber 50 into which the combustible mixtures are conducted through said outlets.

6. In a carbureter, the combination with a plurality of carbureter chambers, each chamber having a main air inlet and an outlet, of a fuel supply nozzle in each chamber, one of said nozzles being permanently in communication with the outlet of its chamber, a valve casing interposed between said inlets and outlets having a plurality of 60 apertures through which air is adapted to flow into said chambers, a cylindrical throttle in said casing common to all of said chambers having openings through which communications are adapted to be established gradually 65 between the main air inlets of said chambers and their respective outlets, said openings being of varying sizes and said throttle being rotatable, whereby said communications are established gradually 70 and in succession, said throttle controlling said apertures and permitting air to flow while the throttle is in its closed position into that chamber the nozzle of which is permanently in communication with the outlet 75 of its chamber, stopping such flow as soon as the throttle is shifted toward its open position, and allowing the passage of air into all of said chambers through said apertures when said throttle is fully opened, 80 and a mixing chamber into which the combustible mixtures are conducted through said outlets.

Signed at New York, in the county of New York and State of New York, this 85 26th day of September, A. D. 1913.

JOHN JUHÁSZ.
